(57) **CLAIM**

The ornamental design for an inhaler as shown and described.

DESCRIPTION

1. Inhaler

1.1 : Perspective

1.2 : Left

1.3 : Right

1.4 : Front

1.5 : Back

1.6 : Top

1.7 : Bottom

1.8 : Opened cover view

Fig. 1 is a perspective view of an inhaler; Fig. 2 is a left side view of an inhaler; Fig. 3 is a right side view of an inhaler; Fig. 4 is a front view of an inhaler; Fig. 5 is a back view of an inhaler; Fig. 6 is a top plan view of an inhaler; Fig. 7 is a bottom plan view of an inhaler; Fig. 8 is a perspective view of an inhaler with cover in the opened position. The broken lines in the drawings depict portions of the inhaler that form no part of the claimed design.
